OSCILLATING OR REVERSING MECHANISM

John W. Conlon, Granby, Conn.

Application August 19, 1943, Serial No. 499,257

2 Claims. (Cl. 121—97)

This invention relates to a fluid actuated oscillating or reversing mechanism for rotary motion through a portion of a revolution.

Many machines in common usage require a certain agitating or opposite motion for their functioning, such as a washing machine, or certain spraying devices for liquids, or in certain machine work it may be desirable where rotation of a part is to be reversed in less than one complete revolution thereof. More or less complicated mechanisms are frequently employed for the obtaining of such a motion as here referred to and where such mechanisms are used certain necessary precision parts are apt to get out of order.

One of the objects of this invention is to provide a device which may be of simple construction with its parts easily manufactured and assembled.

Another object of this invention is to provide a device which may be automatically actuated through the use of fluid power, such for instance as water under pressure.

Another object of the invention is to provide an apparatus which may be adjusted to move oppositely through various angular extents.

With these and other objects in view, the invention consists of certain novel features of construction, as will be more fully described and particularly pointed out in the appended claims.

In the accompanying drawing:

Fig. 1 is an end view of the device;

Fig. 2 is a section of the mechanism;

Fig. 3 is a fragmental sectional view of the casing and the valve mechanism therein and taken on substantially line 5—5 of Fig. 4;

Fig. 4 is a central section taken at substantially line 4—4 of Fig. 1;

Fig. 5 is a section on line 5—5 of Fig. 4;

Fig. 6 is a section on line 6—6 of Fig. 4 with the valve in the same position as shown in Fig. 5.

Fig. 7 is an elevation of the casing block.

In proceeding with this invention I have provided a hollow casing and a rotor member within the casing, the rotor member being sufficiently small with reference to the inside of the casing as to provide an annular chamber. The rotor is provided with an abutment which extends across this chamber and serves as a means to have fluid impinged against it to actuate the rotor. A valve is provided for directing fluid first against one side of the abutment of the rotor and then against the other side with means for automatically shifting the direction of the impinging fluid

so that alternating motion or reversing motion of the rotor member may be produced.

With reference to the drawing, the casing 10 is formed of halves 11 and 12. These halves are placed together as shown in Fig. 4 and held by bolts 13. Each of these halves is substantially cylindrical with circular recesses 14 centrally located. Bearing openings 15 and 16 are provided in each half while a somewhat thickened portion 17 is provided extending outwardly from the periphery of the cylindrical outer surface. Opposite this portion 17 an enlargement also extends inwardly as at 18 by either a part of the casting of the casing or by reason of a separate piece being secured by bolts 19 or by welding thereto. A bore 21 extends through this thickened portion 17, 18 for the accommodation of the valve 22. Conduits cross this bore which are controlled by the valve. As shown in Fig. 3 there are crossing conduits 23 and 24 while the valve 22 has crossing conduits 25 and 26 so arranged that when 26 is in line with 24 conduit 25 is out of registry with conduit 23 and vice versa when conduit 25 is in registry with conduit 23 the conduit 26 will be out of registry with the conduit 24.

At another point axially spaced along the bore 21 there are conduits 27 and 28 which cross the bore 21 while at another point axially spaced 30 along the valve 22 and at a location to align with the conduit 27 and 28 the valve has conduit 29 and 30 so provided that when 29 is in align with 27 conduit 30 will be out of align with conduit 28 and vice versa when 30 is in alignment 35 with 28 the conduit 29 will be out of align with conduit 27.

The rotor is designated generally 31, see Fig. 2, and consists of a hub portion 32 with trunnions 33 and 34 extending axially from either side of this hub portion 32 into the bearings 15 and 16. The hub portion 32 is of a diameter less than the diameter of the recess 14 of the casing so as to provide an annular chamber 35 between the surface of the hub 32 and the inner surface 45 of the casing. An abutment 36 is fastened by means of the bolts 37 to the hub 31 and is of a length substantially the width of the recesses 14 of the interior of the casing. This abutment extends radially entirely across the annular chamber 35 preventing the passage of any fluid past the abutment. Its outer surface 38, of course, has a close fit with the inner circular surface of the recess 14.

With the rotor member 31 assembled in the 55 casing and fluid entering through the conduits

24, 26 (Fig. 5) of the valve the same will impinge the abutment 36 and drive it counterclockwise while any fluid on the other side of this abutment 36 will be driven through the conduit 27 and conduit 29 (Fig. 6) of the casing to exhaust therefrom. Should the valve be shifted to cause conduit 23, 25 to be in alignment and likewise 5 28, 30 opposite rotation will occur.

In order to mechanically shift the valve I have mounted a disc 40 (see Figs. 1 and 4) on the 10 trunnion 34 of the rotor with arms 41 and 42 on this disc in such a position as to engage the laterally extending pin 43 (see Figs. 1 and 4) of the valve. As the disc 40 rotates counterclockwise the arm 41 will strike the pin 43 and shift 15 the valve from the position it is then in to the opposite position described so that fluid which is always impressed upon the conduits 23, 24 will reverse its flow into the annular chamber. Likewise the exhausting ports will be reversed. As 20 the rotor starts in the opposite clockwise direction the arm 42 will then be caused to approach the pin 43 and when this arm strikes the pin 43 the valve will be again shifted. Thus, the rotor will be caused to move in opposite directions and this rotation will alternate through the arc equal to the distance between the arms 41, 42 between which the pin 43 extends. The arms are carried by a U-shape member 45 which may be adjusted along the disc 40 by the arm being threaded through one of the legs of the member and binding on the disc.

In order that the valve may be stopped so that the fluid conduits are in alignment a pin 46 is provided which will engage stops 47 and 48 in 35 the casing to limit the movement of the pin 46 and valve which is actuated.

I claim:

1. An oscillating mechanism comprising a casing, a rotor member rotatably mounted in said casing, said member and casing being so constructed and arranged as to provide an annular chamber between them, an abutment carried by the rotor to extend radially across the said chamber, a boss on said casing extending into said 40 annular chamber in the path of rotation of said rotor abutment, spaced channels extending laterally through said abutment to exhaust fluid from either side of said abutment, a valve intersecting said channels and having spaced pairs of channels extending laterally therethrough, said valve being movable to align one of each pair of channels therein with a channel of each pair of channels in said casing to control the flow of fluid to one channel or the other and at the same time control the flow of exhausting fluid through said other channels, spaced arms carried by said rotor and adjustably movable about the axis of said rotor, a pin fixed to said valve and extending therefrom into the path of travel of said arms to be engaged thereby to move said valve to alternately open and close the flow of fluid through said channels.

2. An oscillating mechanism comprising a casing, a rotor member rotatably mounted in said casing, said member and casing being so constructed and arranged as to provide an annular chamber between them, an abutment carried by the rotor to extend radially across the said chamber, a boss on said casing extending into said annular chamber in the path of rotation of said rotor abutment, spaced pairs of channels extending through said boss to direct fluid against either side of said abutment, and spaced pairs of channels extending through said abutment to exhaust fluid from either side of said abutment, a valve having pairs of spaced channels extending laterally therethrough and with the channels of each pair extending in a plane common to a plane passing through a pair of channels in said casing, said valve being rotatable to align one channel of each pair of channels therein with a channel of each pair of channels in said casing to control the flow of fluid through said channels in said casing and means for automatically switching said valve, said means comprising a pin on said valve and spaced arms carried by the rotor to engage said pin to alternately shift the movement of said valve, said arms being adjustably movable about the axis of said rotor.

JOHN W. CONLON.
